PISTON

Ray E. Day, Detroit, Mich.

Application November 7, 1932, Serial No. 641,532

10 Claims. (Cl. 309—11)

This invention relates to pistons for internal combustion engines, an object of the invention being to control the diameter of the skirt or bearing portions of the piston independently of cylinder wall pressure through the utilization of forces available on account of the relative movement of the wrist pin bosses caused by head expansion and contraction.

A further object of the invention is to provide a piston having a contractible bearing section at one or both sides, and wherein means preferably in the form of diagonal oppositely extending struts is provided and so arranged that the outward movement of the bosses resulting from head expansion will transmit through these struts forces effective to contract the skirt bearing portions, whereby control of the skirt diameter may be obtained under all operating conditions.

Other objects of this invention will appear in the following description and appended claims, reference being had to the accompanying drawings forming a part of this specification wherein like reference characters designate corresponding parts in the several views.

Fig. 1 is a side elevation illustrating a piston embodying the present invention.

Fig. 2 is a horizontal section taken through lines 2—2 of Fig. 1 in the direction of the arrows.

Fig. 3 is a horizontal section taken through lines 3—3 of Fig. 1 in the direction of the arrows.

Fig. 4 is a vertical section taken through lines 4—4 of Fig. 1 in the direction of the arrows.

Fig. 5 is a vertical section taken through lines 5—5 of Fig. 4 in the direction of the arrows.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring to the drawing, wherein there is illustrated one embodiment of the invention, the piston in this instance is preferably formed in a single casting of aluminum alloy, although it is understood that the invention is not limited to this method of producing the piston nor to the particular material utilized. The piston comprises a head having a top portion 9 which directly receives the force of the explosion in the engine cylinder, and also comprises an annular depending flange 10 adapted to be machined to provide ring grooves 11. The flange or side portion 10 of the head is extended downwardly at diametrically opposite sides to provide exteriorly

curved supports 12 and 13 within which are cast a pair of opposed wrist pin bosses 14 and 15 which have aligned openings to receive the wrist pin. This portion of the piston structure is strengthened by means of reinforcing ribs 16 which extend interiorly across the head and integrally embrace opposite sides of the bosses. These ribs preferably have extensions 16a below the bosses.

The piston skirt proper is formed with opposed bearing surfaces extending on opposite sides of 10 the piston between the bosses. These bearing surfaces, in the present instance, are mainly in the form of slipper sections. The bearing section 17 at one side of the piston is preferably continuous and is supported from the head through 15 an integral extension 17a. This bearing portion is partially separated from the head at opposite sides of the supporting portion 17a by means of horizontal annular slots 18.

The lower part of the skirt section 17 is integrally united with circumferential bearing portions 19 disposed below and spaced from the boss supports 13, these bearing portions being in the form of bands forming substantially a complete skirt portion around the lower end of the piston. 25 Diametrically opposite the skirt section 17 are two main bearing portions 20 and 21 which are divided vertically by means of a zigzag slot 22. The upper edges of the sections 20 and 21 are also separated from the head by means of a horizontal slot 23. The cutting 22 at this side of the piston extends continuously from the air gap 23 through the lower bearing portion 19 to the lower edge of the piston. In the present embodiment the bearing portion 20 is formed with a projecting tongue or extension 20a, and this part is joined to the boss 15 by means of a horizontal strut or web 24 which spans the slot 22. The bearing portion 21 in turn is provided with two 30 tongue or projecting portions 21a and 21b located above and below the part 20a and separated therefrom by a part of the zigzag slot 22. The bearing portion 21 is integrally joined to the boss 14 by means of a horizontal strut or web 27, the latter having upper and lower projecting portions 25 and 26 which span the slot 22 and are integrally joined at their ends to the projecting portions 21a and 21b respectively.

From the foregoing it will be seen that one side of the skirt is divided vertically into a pair of bearing portions 20 and 21. The bearing portion 20 which lies in the transverse zone of the boss 14 is connected to the boss 15, more remote from the bearing portion 20, by means of the diagonal strut 24. In like manner the bearing portion 21, which lies in the transverse zone of boss 15, is joined to the boss 14, more remote therefrom, by means of the diagonal strut 27. The struts 24 and 27, the latter including the parts 35 25 and 26, are preferably curved so as to ap- 40 45 50 55 60

proximate the curvature of the skirt portions 20 and 21. The latter, however, are normally incapable, to any substantial extent, of independent yielding movement due to the cross relation of the 5 struts 24 and 27. In other words, the skirt portion 20, 21 is normally non-flexible when compression forces are applied directly to the skirt.

The bearing portion 17 is preferably reinforced to resist distortion by means of a rib 28, and for 10 like reasons the lower edge of the skirt is flanged at 29.

The present invention provides a means for controlling the expansion of the skirt, not by cylinder wall pressure, but solely through the 15 medium of forces transmitted as a result of the outward or inward movement of the bosses caused by the expansion or contraction of the piston head under temperature changes. It will be seen that when the bosses 14 and 15 are moved apart 20 as a result of the head expansion, the boss 14 through the strut 24 will tend to pull the bearing portion 20 inwardly and circumferentially. In like manner the boss 15, when moved outwardly, will, through the strut 27, pull the skirt section 25 21 inwardly and circumferentially. Thus, the outward movement of the bosses will pull the bearing portions 20 and 21 together in a transverse manner, this being permitted by the slot 22. Consequently, the arrangement is such that the 30 expansion of the head will merely result in maintaining the skirt diameter constant thus preventing the skirt from expanding against the cylinder wall. The piston may be initially fitted closely in the cylinder when cold, whereas under operating 35 conditions the tendency of the skirt to expand with the head against the cylinder wall will be prevented since the normal skirt expansion will be counteracted by the contraction of the bearing portions 20 and 21 resulting from the forces 40 transmitted thereto from the bosses through the struts 24 and 27.

I claim:

1. A piston comprising a head, wrist pin bosses and a depending skirt, said skirt having a bearing 45 face at one side between the bosses formed with an upright slot to provide contractible sections, and struts extending from the bosses to said sections to draw said sections together circumferentially when the bosses are moved apart, said 50 struts each spanning said upright slot.

2. A piston comprising a head, wrist pin bosses and a depending skirt, said skirt having a bearing face at one side between the bosses formed with a vertical slot to provide contractible sections, and 55 struts extending diagonally from the bosses to said sections and arranged to draw said sections together circumferentially when the bosses are moved apart, said struts each spanning said vertical slot.

60 3. A piston comprising a head, wrist pin bosses and a depending skirt, said skirt having a bearing face at one side between the bosses formed with a vertical slot to provide contractible sections, and a strut extending from each boss to one of said sections and spanning said slot, said 65 struts being arranged to draw said sections together when the bosses are moved apart through head expansion.

4. A piston comprising a head, wrist pin bosses 70 supported from the head, and a skirt, said skirt at one side between the bosses having a pair of contractible bearing sections provided with interfitting circumferential projecting portions sep-

arated by a zigzag slot, and struts extending from the bosses to said sections and each having a curvature approximating the curvature of the skirt, said struts being arranged to contract said sections, one independently of the other, when 5 the bosses are moved apart through head expansion.

5. A piston comprising a head, wrist pin bosses supported therefrom, a skirt having at one side between the bosses a pair of vertical bearing portions provided with staggered interfitting extensions separated by an irregular slot, diagonal struts extending from the bosses to the bearing portions and arranged to lessen the expansion of the skirt diameter by relatively moving said bearing portions when the bosses move apart relatively to each other.

6. A piston comprising a head, a skirt, wrist pin bosses supported from the head, said skirt at one side thereof being separated by a vertical slot to 20 form two adjacent bearing portions, a strut connecting each boss with the bearing portion at the far side of said vertical slot, said struts being arranged to draw said bearing portions together when the bosses are moved apart through head 25 expansion.

7. A piston comprising a head, a skirt, and wrist pin bosses connected to the head, said skirt at one side being vertically separated by a zigzag slot between the bosses to provide two adjacent 30 bearing portions, a pair of independently movable struts, each of said struts connecting one of said bearing portions with the boss lying in the transverse zone of the other bearing portion.

8. A piston comprising a head, a skirt, and wrist 35 pin bosses connected to the head, said skirt at one side being vertically separated to provide two adjacent bearing portions, a strut connecting each boss with the bearing portion at the far side of the vertical separation between said bearing 40 portions, said bearing portions being normally rigid against movement under pressure and said struts being arranged to move said bearing portions toward each other through forces transmitted from the bosses when the latter are moved 45 apart by head expansion.

9. A piston comprising a head having depending integral supports, a pair of aligned wrist pin bosses carried by said supports, a skirt comprising a bearing section at one side integrally joined 50 to the head and a bearing section at the other side separated from the head, said last bearing section being divided longitudinally into two adjacent contractible bearing portions, and a strut extending laterally from each boss to the bearing portion at the far side of the longitudinal division, said struts being effective to maintain said bearing portions substantially non-yieldable under 55 external pressure while operating to transmit oppositely directed forces to the bearing portions 60 from the bosses.

10. A piston comprising a head, wrist pin bosses supported therefrom, a skirt having at one side between the bosses a pair of bearing portions provided with interfitting projections separated by a 65 zigzag slot, diagonal strut members extending in close proximity to the inner face of the bearing portions from the bosses to said bearing portions and arranged to lessen the expansion of the skirt 70 diameter by relatively moving said bearing portions when the bosses move apart relatively to one another.
